AND ONE-HALF TO LOUIS DROGIN, BOTH OF NEW YORK, N. Y.

BATH-SPRAY.

1,102,736.

Specification of Letters Patent.

Patented July 7, 1914.

Application filed January 16, 1914. Serial No. 812,458.

To all whom it may concern:

Be it known that I, HANS E. GRABAU, a citizen of the United States, residing in New York city, county and State of New York, have invented certain new and useful Improvements in Bath-Sprays, of which the following is such a full, clear, and exact description as will enable any one skilled in the art to which it appertains to make and use the same, reference being had to the accompanying drawings, forming part of this specification.

My invention relates to a spray apparatus used with bath tubs, and the principal objects of my invention are to provide a device of this class in which the spray-nozzle may be easily and quickly turned or adjusted in any desired position, and to maintain its position of adjustment without the aid of the user or without external support, and to provide a spray-nozzle which will project or throw a series of sprays in directions different from each other, and which may be directed to practically a common point, and further to provide a simple means of detachably mounting the bath-spray in operative position.

With these and other objects in view, my invention consists in the various novel and peculiar arrangements and combinations of different parts of the apparatus, all as hereinafter fully described and then pointed out in the claims.

I have illustrated types of my invention in the accompanying drawings, wherein:—

Figure 1 is a side view of a bath tub equipped with my improvements, one end of the tub being broken away to show the fixture within the tub. Fig. 2 is a side view of the clamp for detachably mounting the bath-spray upon the faucet or fixture of the tub. Fig. 3 is another view of the clamp for detachably securing the bath-spray in place, the clamp being adjusted in a position at right angles to that shown in Fig. 2. Figs. 4 and 5 are views of a modified form of the clamp for detachably securing the bath-spray in place upon the fixture, the views of the clamp being taken at right angles to each other. Fig. 6 is an enlarged view of one of the spray-nozzles shown in Fig. 1, the nozzle being here shown as turned on its axis through a half circle to invert it, the dotted line position showing the nozzle as adjusted in a downwardly pointing position. Fig. 7 is a side view of a modification of the bath-spray and shows the nozzle supporting pipe, which is of flexible metal, being made comparatively long and itself supported by a clamp at its lower end, and the clamp being shown as attached to the vertical part of a faucet. In this view the dotted lines show the spray-nozzle in a different position of adjustment. Fig. 8 is a side view of a modification of the pipe for supporting the spray-nozzle, the pipe here shown being a flexible metal pipe having solid cylindrical walls as contradistinguished from the corrugated flexible metal pipe shown in Fig. 7. In this view the dotted lines show the spray-nozzle as moved into a different adjustment. Fig. 9 is an enlarged front view of my improved spray-nozzle shown as detached. Fig. 10 is a horizontal sectional view of the spray-nozzle shown in Fig. 9, the plane of the view being indicated by line 10—10, Fig. 9. Fig. 11 is a central vertical sectional view of the spray-nozzle shown in Fig. 9. Fig. 12 is a diagrammatic view showing the respective lengths of a pair of arc-shaped nozzles when used together upon the same pipe.

Referring to the drawings in which like numbers of reference designate like parts throughout, my improved spray-nozzle indicated by the numeral 1 is shown as constructed of sheet metal and is of an elongated shape made substantially in the form of an arc, and with the face thereof provided with a plurality of groups of spray-holes 2, 3 and 4. The nozzles are hollow practically throughout, and the face thereof which bears the groups of spray-holes is made in a peculiar form, as indicated in the drawings, and so that each group of spray-holes or rose is in a different plane from that of the adjacent group or groups. For example, assuming that the nozzle is set so that the plane containing the group of spray-holes 3, stands in a vertical plane, the planes containing the other two groups 2 and 4, make an obtuse angle with the said vertical plane, and the said planes containing the groups 2 and 4, intersect when prolonged. It will be further noted that the planes containing the various groups of spray-holes are each oblique to the axis about which the spray-nozzle may be turned,

as hereinafter described. The purpose of having the groups of spray-holes thus arranged is to provide a plurality of sprays which coming from different points of the elongated nozzle may converge and be thrown against practically a common point, thus preventing the sprayed water from being thrown beyond the sides of the bath tub.

5 The length of the arc form of the nozzle 10 may be made longer or shorter, as desired, and the angles between the planes containing the different groups of spray-holes may be varied to control in the desired manner the direction of each spray relative to the others, the face of the nozzle being bowed.

15 The back of the spray-nozzle is provided with a tubular part 5, which fits within the tubular end 6, of the nozzle-supporting pipe 8, the joint between the two parts 5 and 6, 20 being a friction-joint for permitting the ready coupling and uncoupling of the parts and enabling the operator to rotate the nozzle on its support, thereby permitting him to adjust the arc-shaped nozzle at any angular position relative to its support. Thus it 25 can be completely inverted when desired, the friction-joint of course being capable of holding the nozzle against dislodgment by the force of the water, the inverted position 30 of the nozzle being shown in Fig. 6.

The pipe 8 both supports the nozzle and supplies the water thereto and this pipe is a flexible metal one and has such flexibility as not to require external support to give it 35 the necessary rigidity to retain its position of adjustment, so that it can be flexed or bent by hand into any desired position in order to change the direction in which the sprays are thrown by the nozzle. This is an 40 important feature of the invention, and it is carried out by means of a flexible metal pipe having the described capacity, and for this purpose I use either an ordinary corrugated flexible metal pipe, which is found as a commodity upon the market, or I use a cylindrical metal pipe having solid non-corru- 45 gated walls, and made of a suitable metal such as block-tin, which will permit of the pipe being readily flexed or bent by hand 50 without much force, but at the same time has the described rigidity, that is to say, it will retain itself in the adjusted position without external support, a non-corrugated pipe for the nozzle of the kind described 55 being shown at 8^b in Fig. 8.

In Figs. 1 to 6, inclusive, I show the flexible metal nozzle-supporting pipe 8, as connected with a rigid metal pipe 9, which is detachably mounted in a clamp 10, which 60 is clamped to an ordinary faucet 11, of a bath-tub 12, the faucet 11, being supplied in the usual way with both hot and cold water, one of the supply-pipes of the faucet being indicated at 13. The rigid pipe 9, is provided near its lower end with a tubular lat-

eral extension 14, which has its outside formed with a spiral rib 15, (see Fig. 5), and when the pipe 9, is mounted in vertical position in the clamp, a rubber tube 16, is coupled between the nozzle of the faucet 11, 70 and the ribbed extension 14, of the pipe 9, so that when the faucet is opened water is supplied to the vertical pipe 9. In Fig. 1 I show a pipe 9, as being provided with a pair of my improved nozzles 1, each being at- 75 tached to and supported by a flexible metal pipe 8, receiving the water from the pipe 9. This pipe 9, is provided with a cock 17, for cutting off the upper nozzle, and a similar cock 18, for cutting off both nozzles when 80 desired. In using a pair of nozzles arranged one above the other, I prefer to make the lower nozzle longer than the upper one, as indicated in the diagrammatic view in Fig. 13, in order to give a greater spread to the 85 spray, for the reason that the lower nozzle directs its sprays well within the confines of the tub without liability of throwing the spray beyond the sides thereof.

In the arrangement shown in Figs. 1 to 90 6, inclusive, the length of the flexible metal pipe 8, for supporting the spray-nozzles and supplying water thereto should be sufficient to permit of such pipe being readily flexed by hand in any direction about the point 95 of support of the pipe, so that the user can easily bend the pipe into whatever position he may desire in order to control the direction in which the sprays are thrown by the nozzle. In Fig. 1 the flexible pipe 8, of 100 the upper nozzle is shown as adjusted in a substantially horizontal position, so that the sprays will be thrown in arc-form when viewed from the side, and as substantially indicated by the dotted lines, while the flex- 105 ible pipe of the lower nozzle is bent downwardly so that the sprays from the lower nozzle are thrown more directly downwardly into the tub, as indicated by the dotted lines. In Fig. 6 the flexible pipe 8, of the spray-nozzle is shown as bent upwardly, which position may be desired when the nozzle is mounted at a very low point. The dotted line position in Fig. 6 shows the 110 flexible metal pipe as bent downwardly substantially on the order of the lower nozzle- 115 pipe in Fig. 1.

In Fig. 7 I show a construction in which the flexible metal pipe 8^a, is made of sufficient length to take the place of the rigid pipe, shown in Figs. 1 to 6, inclusive. In this construction the flexible pipe 8^a, is secured directly to the clamp 10, which is attached to the depending vertical part of the faucet 11, and the lower end of the flexible pipe 8^a, is provided with a smooth coupling-piece 19, over which is slipped one end of the rubber tube 20, the other end of such tube being slipped over the end of the faucet 11, to connect the faucet with the 120 125 130

flexible pipe, the rubber tube 20, being provided at each end with an enlarged coupling-piece 21. The flexible pipe 8^a may be twisted in any direction about its vertical axis, as shown in the drawings, and it may also be bent or flexed laterally in the position desired, the dotted lines in Fig. 7 showing the pipe bent somewhat upwardly with the nozzle directed downwardly. In order 10 to protect the hand of the user in manipulating the corrugated form of flexible pipe, I provide a hand-grip in the form of a sleeve 22, which is made of a soft material such as felt or leather.

15 In Fig. 8 I show the same form of construction as in Fig. 7, with the exception that the flexible pipe 8^b has a smooth exterior, instead of a corrugated one. As hereinabove stated, this pipe may be made of 20 block-tin or a metal having the same capacity of flexibility and rigidity.

It will thus be seen that by virtue of having the supporting-pipe of the nozzle made of a flexible metal having at the same time 25 a certain degree of rigidity, as above pointed out, and having the spray-nozzle so mounted upon such a pipe that the nozzle may be turned on its axis into any adjustment thereon, I provide a device in which 30 the spray-nozzle has, what I may term, universal capacity of adjustment. One of the important advantages in using a flexible pipe on the order of that described is, that all movable joints are dispensed with, and 35 I am further able to use ordinary flexible metal pipe as found upon the market.

The character of the flexible metal pipe which supports the spray-nozzle and permits of its universal adjustment is such 40 as to readily admit of being bent, bowed or twisted by hand without breaking or rupturing, and at the same time has sufficient rigidity to maintain its position of adjustment without external support and without 45 liability of being moved out of such adjustment by the pressure or force of the body of water passing through the pipe. This pipe may be repeatedly flexed and twisted without destroying it or incapacitating it in 50 the performance of its function of providing a secure conduit for the passage of water under pressure and of remaining in its adjusted position without the aid of external support.

55 The clamp 10, for detachably securing the rigid pipe 9, or the flexible pipe 8, to the faucet 11, is provided with two pipe-receiving sockets 22 and 23 respectively, which are located at right angles to each other, 60 the socket 23 in the end of the clamp being used to receive the pipe when mounted upon the horizontal part of the faucet 11, as indicated in Figs. 1, 2 and 3, respectively, while the other socket 22, is used for holding the 65 pipe when the clamp is mounted upon the

vertical part of the faucet 11, as indicated in Figs. 3, 7 and 8.

The clamp shown in Figs. 1, 2, 3, 7 and 8, is composed of two similar members 24 and 25, the inner face of the respective members being 70 formed with recesses 26 and 27, respectively, which form a socket for receiving the part of the faucet 11, on which the clamp is mounted. At another point on the inner faces of the clamping members are recesses 28 and 75 29 for forming the socket 22, for holding the pipe, while at the end of the clamping members the opposite inner faces of the members are recessed at 30 and 31, respectively, to form the socket 23, for receiving 80 the pipe. The set-screws 32 and 33, are provided at each end of the clamping members to bind them together, and a third set-screw 34, is arranged near the center of length of the members as an additional means for 85 clamping the members upon the faucet.

In Figs. 4 and 5 I show a modified form of the clamp and in which the clamp is composed of a single member, one end of which is formed with a ring 36, into the sides of 90 which are let a series of set-screws 37, which point toward the center of the circle, and the inner ends of which screws engage the part of the faucet 11, on which the clamp is mounted. From one side of the annular 95 part or ring 36 projects a boss in which is formed laterally a socket 38, and in the end of this boss is formed another socket 39, running at right angles to the socket 38, and the two sockets intersecting. A set-screw 40, is let into the side of the boss so as to coöperate with either socket 38 or 39. When this clamp is secured to a vertical 100 part of the faucet 11, as indicated in Fig. 4, the pipe 9, of the spray-device is inserted in the socket 38, and the set-screw 40, holds it in the socket. When this clamp is mounted upon a horizontal part of the faucet 11, as shown in Fig. 5, the pipe 9, of the spray-device is inserted in the end socket 39, and 110 the set-screw 40, is turned down against the pipe so as to securely hold it in the socket.

In the operation of my improved spray-device, it will be readily understood that the user of the device may before turning the 115 water on set the nozzle in a desired position to spray a particular part of his body, by turning the nozzle on its point of support or flexing the supporting pipe, or both, and that after such adjustment of either or both of these parts, it is unnecessary for the user to hold any part of the apparatus with his hand, so that both hands are left free for use in bathing.

The plurality of sprays coming from each 125 nozzle, provides a profuse and well-diffused shower, the jets in which are closely disposed, and by using several of the nozzles as shown, the best results are quickly obtained in the way of a thorough drenching and 130

washing of the bather and particularly where the lower nozzle is much elongated, as it can be and still directs its sprays within the tub.

5 Having thus described my invention, what I claim and desire to secure by Letters Patent is:

1. A bath-spray comprising a spray-nozzle and a pipe for supplying water thereto, the said spray-nozzle being elongated and of considerable width and having its front face curved or bent to form it into a series of substantially flat plane surfaces forming angles with each other and each flat surface being provided with a group of spray-holes, the said groups of spray-holes being adapted to project their sprays at angles to each other but in a converging direction to con-
- 10
- 15

fine the sprays within the bath-tub, substantially as described.

2. A bath-spray comprising a spray-nozzle and a pipe connected with said nozzle and supplying water thereto, the said spray-nozzle being elongated and provided with a series of spaced groups of spray-holes disposed substantially in a vertical arc form and each disposed in substantially a different plane from the others, substantially as described.

20 In testimony whereof I have hereunto set my hand in the presence of the two subscribing witnesses.

HANS E. GRABAU.
